UNITED STATES PATENT OFFICE.

HERMANN STRUMPF, OF BERLIN, GERMANY.

ATOMIZER.

1,035,261.

Specification of Letters Patent. Patented Aug. 13, 1912.

Application filed February 16, 1912. Serial No. 678,145.

To all whom it may concern:

Be it known that I, HERMANN STRUMPF, a subject of the King of Prussia, and resident of 185 Oranienstrasse, Berlin, Kingdom of Prussia, German Empire, have invented certain new and useful Improvements in Atomizers, of which the following is a specification.

This invention relates to portable atomizers or spray-producers of the type in which a piston is moved within a cylinder under the action of a spring to eject the fluid to be atomized through a nozzle and in which the piston is drawn back against the action 10 of the spring so as to enable the cylinder to be filled with liquid ready for the next operation, and the object of the present invention is to improve and simplify the construction and manipulation of such atomizing apparatus.

According to the present invention a screwed spindle passing through the closed end of the cylinder is threaded through a nut secured against rotation but slideable in 20 a preferably angular casing projecting from the piston so that on rotating said spindle in one direction the nut is threaded thereon and draws back the piston against the action of the spring. The cylinder may then be 30 filled and for this purpose it is preferably provided with a funnel-shaped neck at its open end into which the nozzle-casing may be screwed, and the bore of the nozzle is preferably provided with a screw-down 35 valve so that by closing the bore of the nozzle and rotating the screwed spindle in the opposite direction, the nut threaded thereon will be slidably moved in its guide-casing, so as to free the piston, whereupon 40 on opening said valve, the piston will be moved under the action of the spring and eject the liquid through the nozzle. By this means the piston is efficiently guided in its to and fro movement.

45 In order that the invention may be more clearly understood, reference is made to the accompanying drawings, which show by way of example the preferred method of carrying out my invention.

50 Figure 1 is a vertical section through the atomizing apparatus, Fig. 2 is a transverse section on the line A—B of Fig. 1, and Fig. 3 is a detail view of one part of the nozzle hereinafter more fully referred to.

55 The atomizer consists essentially of a preferably cylindrical casing 1 closed at one

end by means of a block 3 secured thereto by means of screws 2. The other end of the cylinder is provided with a neck portion 4 terminating in a funnel-shaped part 5. 60 Within the cylinder is arranged a piston 6 which consists of a rear plate 7, a leather cup 8, and a clamping plate 9 clamping the leather cup 8 and an intermediate cup-shaped piece 10 between it and the rear 65 plate 7, the parts being secured together by means of screws 11 screwing into internally screwed projections 13 on the rear plate 7. The leather cup 8 is pressed outwardly into contact with the cylinder wall 70 by means of a spring ring 12.

Integral with and projecting from the rear plate 7 is a preferably triangular prismatic casing 14 having an opening 15 at one end through which passes a screwed 75 spindle 16 which is provided at its lower end with a flange 17 rotatable in a corresponding groove in the block 3 and provided with a rectangular recess 18 for the reception of a screw key or other manipulating 80 device 19. Threaded on the spindle 16 is a nut 20 which is capable of a sliding movement within the casing 14 but which is prevented from rotation therein owing to the triangular cross-section of the casing 14, 85 which construction enables the employment of an ordinary hexagonal nut 20, as may be seen in Fig. 3. Fast on the end of the screw spindle 16 is secured an abutment 21 which may be riveted or otherwise secured 90 thereto. A spring 22 contained within the cylinder 1 and bearing at one end against the block 3 and at its other end against the rear plate 7 of the piston 6 tends to force the piston 6 toward the neck-shaped end 4. 95

It is preferable to employ a guide casing 14 of triangular cross section as shown in the drawing owing to the economy thereby attained in constructional material. The casing 14 may however be of any other desired cross section, although when of circular cross section it is necessary that provision be made for preventing rotation of the nut 20 therein. The casing 14 not only serves to guide the nut 20 but also constitutes a guide for the piston 6 in as much as the casing 14 is constructed preferably so that its apical edges almost contact with the surrounding spring 22, as may be seen in Fig. 2, so that by this means any displacement of the piston 6 in the cylinder 1 is prevented.

The reduced neck portion 4 of the atomizing device is provided with an internally threaded neck piece 23 into which is adapted to be screwed the threaded end of the valve 5 casing 24 which is for this purpose provided with a milled hand wheel 25. The casing 24 is provided with a narrow central bore 26 adapted to be closed by means of a preferably cone valve 27 which can be raised 10 and lowered by means of a milled hand wheel 28 secured on the spindle 29 of the valve, which is provided with a narrow central bore 30 terminating at its lower end in lateral orifices 31 opening into a valve chamber 15 in the valve casing 24. 32 designates packing around the valve spindle 29 held in position by means of a screwed cap 33. The upper end of the valve spindle 29 is provided with a flange 34 and is externally 20 threaded to receive an internally threaded nozzle 35 having a narrow outlet orifice 36. Screwed into the nozzle 35 is a cylindrical externally threaded element 37 (shown in detail in Fig. 3) which is provided at its 25 lower end with a reduced extension 38 to enable it to be screwed into the nozzle 35 and exteriorly provided with a spiral groove 39 which connects the bore 30 of the valve spindle 29 with a shallow chamber 40 in the 30 rear of the discharge orifice 36.

The operation of the improved atomizing apparatus is as follows:—In order to fill the atomizer with liquid, the valve casing 24 together with the valve 27 and nozzle 35 35 is screwed out of the neck piece 23. Thereupon the screwed spindle 16 is rotated in one direction by means of a crank or the like 19 and the nut 20 thereby threaded over the screwed spindle 16, thus drawing back 40 the casing 14 together with the piston 16 in the cylinder 1, thereby compressing the spring 22.

In the example illustrated on the drawing the piston 6 is capable of being moved 45 over approximately one half of the length of the cylinder 1. When the piston 6 has been drawn back in the manner hereinbefore described, the upper part of the cylinder 1 may be filled with liquid through the funnel 5 and the valve casing 24 again screwed 50 into the neck piece 23. The valve 27 is then screwed down by means of the hand wheel 28 so as to close the port 26. The screwed spindle 16 is then rotated in the opposite 55 direction by turning the crank 19 and by this means the nut 20 is threaded in the reverse direction on the screwed spindle 16 until it abuts against the abutment plate 21. The valve 27 may thereupon be raised from 60 its seating, thus freeing the piston 6 which under the action of the spring 22 forces the liquid out of the cylinder 1 through the port 26, orifices 31 and port 30 and thence through

the spiral groove 39 and out at the discharge nozzle 36 in the form of a fine spray. 65

I claim:—

1. Atomizing apparatus comprising a cylinder closed at one end, a rotatable screwed spindle passing through said closed end, a nut threaded on said spindle, a piston movable in said cylinder, a hollow guide casing projecting from said piston and inclosing said nut so as to prevent the latter from rotation but enable it to slide therein, a spring tending to force said piston toward the open end of said cylinder, and a nozzle fitted on said open end. 70

2. Atomizing apparatus comprising a cylinder closed at one end, a rotatable screwed spindle passing through said closed end, a prismatic nut threaded on said spindle, a piston movable in said cylinder, a hollow prismatic casing projecting from said piston, and inclosing said nut so as to prevent the latter from rotation but enable it to slide therein, a spring tending to force said piston toward the open end of said cylinder and a nozzle fitted on said open end. 75

3. Atomizing apparatus comprising a cylinder closed at one end and funnel-shaped at its other end, a rotatable screwed spindle passing through said closed end, a nut threaded on said spindle, a piston movable in said cylinder, a hollow guide casing projecting from said piston and inclosing said nut so as to prevent the latter from rotation but enable it to slide therein, a spring tending to force said piston toward the open end of said cylinder, and a detachable nozzle fitted on said open end. 90

4. Atomizing apparatus comprising a cylinder closed at one end and funnel-shaped at its other end, a rotatable screwed spindle passing through said closed end, a nut threaded on said spindle, a piston movable in said cylinder, a hollow guide casing projecting from said piston and inclosing said nut so as to prevent the latter from rotation but enable it to slide therein, a spring tending to force said piston toward the open end of said cylinder, a detachable valve casing on the funnel-shaped end of said cylinder having a central bore and valve chamber, a screw-down valve in said valve chamber and in axial alignment with said central bore, said valve having a central bore communicating through lateral orifices with said valve chamber, and a discharge nozzle carried by said valve. 105

In witness whereof I have hereunto set 110 my hand in the presence of two witnesses.

HERMANN STRUMPF.
